UNITED STATES PATENT OFFICE.

IRA G. NICKS, OF DENVER, COLORADO, ASSIGNOR TO THE JOY TOY MANUFACTURING COMPANY, OF DENVER, COLORADO, A CORPORATION OF COLORADO.

DESIGN FOR A TOY VEHICLE.

Application filed March 20, 1926. Serial No. 16,994. Term of patent 7 years.

To all whom it may concern:

Be it known that I, IRA G. NICKS, a citizen of the United States, residing at the city and county of Denver and State of Colorado, have invented a new, original, and ornamental Design for Toy Vehicles, of which the following is a specification, reference being had to the accompanying drawing, forming a part thereof, and in which:

Figure 1 is a perspective view of the vehicle; and

Figure 2 is a top plan view of the vehicle.

I claim:

The ornamental design for a toy vehicle, as shown.

In testimony whereof I affix my signature.

IRA G. NICKS.
